DESIGN FOR A CLOTHES HAMPER

Jackson H. Stone, Los Angeles, Calif., assignor to Allied Wood Products Company, Los Angeles,
Calif., a corporation of California

Application December 20, 1943, Serial No. 112,060

Term of patent 3½ years

(Cl. D58—4)

To all whom it may concern:

Be it known that I, Jackson H. Stone, a citizen of the United States and a resident of the city of Los Angeles, county of Los Angeles, State of California, have invented a new, original, and ornamental Design for a Clothes Hamper, of which the following is a specification, reference being had to the annexed drawing, forming a part thereof.

Fig. 1 is a perspective view of a clothes hamper, showing my design;

Fig. 2 is a top plan view thereof;
Fig. 3 is a front view thereof, which is also illustrative of the back thereof;

Fig. 4 is a side view thereof; and

Fig. 5 is a perspective view thereof, showing the cover lid partially raised.

I claim:

The ornamental design for a clothes hamper, substantially as shown.

JACKSON H. STONE.
